(57) CLAIM

I claim, the ornamental design for a chair, as shown and described.

DESCRIPTION

FIG. 1 is a perspective view of a chair, showing a first embodiment of my new design;

FIG. 2 is a front view thereof;

FIG. 3 is rear view thereof;

FIG. 4 is a side view thereof;

FIG. 5 is an opposite side view thereof;

FIG. 6 is a top view thereof;

FIG. 7 is a perspective view thereof, showing a second embodiment of my new design;

FIG. 8 is a front view thereof;

FIG. 9 is rear view thereof;

FIG. 10 is a side view thereof;

FIG. 11 is an opposite side view thereof; and,

FIG. 12 is a top view thereof.

The portions of the chair illustrated in broken lines form no part of the claimed design.
